GUY WIRE FASTENER

Robert Schaebler, Hatfield, Pa.

Application September 20, 1939, Serial No. 295,841

3 Claims. (Cl. 24—132)

This invention pertains to guy wire fasteners of the type generally similar to that constituting the subject matter of my U. S. Patent No. 2,064,952, issued Dec. 22, 1936, upon which the present device constitutes an improvement.

An important object of the present invention is to provide, in a manner as hereinafter set forth, a fastener of the aforementioned character comprising novel means whereby the clamping elements may be retained in inoperative position to facilitate insertion of the end portion of the cable or guy wire.

Another very important object of the invention is to provide a guy wire fastener of the character described embodying a construction and arrangement which is such that the device may be expeditiously assembled.

Other objects of the invention are to provide a guy wire fastener of the character set forth which will be comparatively simple in construction, strong, durable, highly efficient and reliable in use, compact and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a vertical sectional view through a guy wire fastener constructed in accordance with the present invention.

Figure 2 is a view in side elevation thereof.

Figure 3 is an elevational view, taken at right angles to Fig. 2.

Figure 4 is a view in horizontal section, taken substantially on the line 4—4 of Fig. 2.

Figure 5 is a vertical sectional view substantially similar to Fig. 1 but showing the clamping rollers retained in inoperative position.

Figure 6 is a vertical sectional view, taken substantially on the line 6—6 of Fig. 5 with the cable or guy wire omitted.

Figure 7 is a detail view in perspective of one of the pivot pins.

Figure 8 is a perspective view, showing a slight modification.

Referring now to the drawings in detail, it will be seen that the reference numeral 1 designates a substantially ovate plate of suitable metal having formed in its edge or periphery a spirally ribbed groove 2 for the reception of an end portion of a guy wire, as at 3. Also formed in the plate 1 is a vertical slot 4. The reference

numeral 5 designates a pair of recesses which are formed in the periphery of the plate 1 at intermediate points.

Mounted adjacent the upper portion of the plate 1 and movable vertically independently of said plate is a pair of horizontal metallic bars 6. Connecting the pair of bars 6 and extending therethrough and therebeyond is a pair of pins 7. Peripherally grooved clamping rollers 8 are journaled on the pins 7 between the bars 6. 10

Journaled on the projecting end portions of the pins 7 and depending therefrom are pairs of slotted metallic links 9. Extending between the lower end portions of the pairs of links 9 are pins 10. Journaled on the pins 10 between the 15 lower portions of the links 9 are comparatively large, peripherally grooved clamping rollers 11.

The reference numeral 12 designates pairs of metallic links having one end portion journaled on the pins 10 between the rollers 11 and the 20 lower end portions of the links 9. The other end portions of the links 12 are journaled on a pin 13 which is operable vertically in the slot 4 in the plate 1.

The pins 7, 10 and 13 are substantially similar 25 in construction. Referring to Fig. 7 of the drawings, it will be observed that the pin 13 includes reduced end portions or necks 14 terminating in heads 15. Mounted on the end portions of the pin 13 is a clevis 16. The clevis 16 has formed 30 in its end portions keyhole slots 17 for the reception of the reduced end portions 14 of the pin 13. The reference numeral 18 designates a bar which is insertable in the lower portions of the keyhole slots 17 and the slot 4 for engagement beneath the lower end portions of the links 12 for holding the clamping rollers 8 and 11 in raised or inoperative position when desired. 35

It is thought that the manner in which the device functions will be readily apparent from a consideration of the foregoing. As shown to advantage in Figs. 5 and 6 of the drawings, the bar 18 is inserted through the lower portions of the slots 17 and 4 for retaining the clamping rollers 8 and 11 in raised position. The end portion of the guy wire 3 may then be conveniently inserted in the device, said guy wire traversing the arcuate recesses 5. The bar 18 is then removed and when a pulling force is exerted on the clevis 16 the guy 50 wire is firmly clamped between the plate 1 and the rollers 8 and 11. The construction and arrangement is such that the greater the pull to which the device is subjected, the greater will be the clamping action on the guy wire. 55

The keyhole slots 17 permit the clevis 16 to be expeditiously removed or detached when desired. In Fig. 8 of the drawings, the reference numeral 19 designates a cable which may be connected to the fastener in lieu of the clevis 16. Toward this end, the cable 19 has secured on its end portions a pair of ears or the like 20 having formed therein keyhole slots 21 for the reception of the end portions of the pin 13. This arrangement 10 may be used for connection with a pole, also for connecting insulators, if desired.

It is believed that the many advantages of a guy wire fastener constructed in accordance with the present invention will be readily understood 15 and although preferred embodiments of the device are as illustrated and described, it is to be understood that further modifications and changes in the details of construction may be resorted to which will fall within the scope of the 20 invention as claimed.

What is claimed is:

1. A guy wire fastener comprising a substantially ovate plate having a peripheral groove therein for the reception of an end portion of a guy wire, said plate further having a vertical slot therein, a pair of bars extending horizontally adjacent the small end portion of said substantially ovate plate and movable relative thereto, clamping rollers journaled between said bars, pairs of links pivotally connected to the bars, clamping rollers journaled between said links, the first and second named rollers being cooperable with the plate for clamping the guy wire therebetween, links pivotally connected to the first named links, a pin pivotally connecting the second named links at one end, said pin being oper-

able in the slot in the plate, a clevis mounted on the pin and having keyhole slots in its end portions for the reception of said pin, the pin comprising heads on its ends, and a bar engageable in the slots beneath the second named links for holding the rollers in inoperative position.

2. A guy wire fastener of the class described comprising a substantially ovate plate having a slot therein, a pin operable in the slot, said pin including reduced end portions terminating in heads, a clevis mounted on the pin and having keyhole slots in its end portions for the reception of the reduced end portions of the pin, links pivotally connected to the pin, rollers journaled on said links and cooperable with the plate for clamping a guy wire therebetween, and a member engageable in the lower portions of the slots beneath the links for holding the rollers in inoperative position.

3. A guy wire fastener comprising a substantially ovate plate having a slot therein, a pin operable in the slot, said pin including reduced end portions terminating in heads projecting beyond the sides of the plate, pairs of links pivotally connected to the pin, rollers journaled between the pairs of links, said rollers, in conjunction with the plate, constituting means for clamping an end portion of a guy wire, a connector adapted to be detachably coupled to the pin, said connector having keyhole slots in its end portions for the reception of the reduced end portions of the pin, and a member engageable in the lower portions of the slots beneath the links for holding the rollers in inoperative position.
